CLAIM

We claim the ornamental design for a detergent container for washing machine, as shown and described.

DESCRIPTION

FIG. 1 is a front perspective view of a detergent container for washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view of the detergent container for washing machine shown in an alternate position.

The broken lines in the figures show portions of the detergent container for washing machine which form no part of the claimed design.

1 Claim, 6 Drawing Sheets
